UNITED STATES PATENT OFFICE.

CLEVE T. SHAFFER, OF SAN FRANCISCO, CALIFORNIA, ASSIGNOR TO A. SCHRADER'S SON, INCORPORATED, OF BROOKLYN, NEW YORK, A CORPORATION OF NEW YORK.

VALVE-STEM CLOSURE.

Application filed September 10, 1917, Serial No. 190,443. Renewed April 6, 1921. Serial No. 459,012.

To all whom it may concern:

Be it known that I, CLEVE T. SHAFFER, a citizen of the United States, residing at the city and county of San Francisco and State of California, have invented certain new and useful Improvements in Valve-Stem Closures, of which the following is a specification.

The present invention relates to improvements in dust guards for valve stems, and is designed for protecting the valve stem and at the same time, to provide a hermetic seal for the open end of the valve, thus dispensing with the valve cap which is now employed in connection with the present form of dust guard.

The present invention has for its principal objects to provide a construction which is capable of loose positioning on the valve stem, and on a slight rotative movement thereof, is adapted to be locked thereon, tightly sealing the open end of the stem. To provide a construction wherein the same is adapted for adjustment to enclose stems projecting various lengths through the felloe, and at the same time, to hermetically seal the open end thereof. To provide a construction, which is designed particularly for use in connection with the present form 30 of valve stem which is formed with longitudinal extending flat faces at opposite sides thereof, which provide an interrupted thread extending for the full length of the stem.

The invention consists broadly in a body member, provided adjacent its lower edges with an inwardly projecting portion, which is adapted, when positioning or removing the body from the stem, to lie adjacent the interrupted portions of the thread of said 40 stem, and is adapted on the rotating of the body, to engage the threads on the stem and tightly draw the body over the open end of the stem, thus sealing the stem and protecting the body thereof.

With the above mentioned and other objects in view, the invention consists in the novel construction and combination of parts, hereinafter described, illustrated in the accompanying drawings, and pointed out in the claims hereto appended, it being understood that various changes in the form, proportion, size and minor details of construction within the scope of the claims 50 may be resorted to without departing from

the spirit or sacrificing any of the advantages of the invention.

To more fully comprehend the invention, reference is directed to the accompanying drawings wherein,

Fig. 1 is a vertical sectional view of the preferred embodiment of my invention loosely positioned on the valve stem.

Fig. 2, is a view similar to Fig. 1, illustrating the body member rotated to position, the inturned thread engaging portion thereof in engagement with the threads of the stem.

Fig. 3 is a sectional view taken on the line 3—3 of Fig. 1.

Fig. 4 is a sectional view taken on the line 4—4 of Fig. 2.

Fig. 5 is a view in plan of the lower end of the guard.

Referring more particularly to the several views of the drawings, wherein like characters of reference designate corresponding parts, 1, indicates a wheel felloe, through which projects the tire valve stem 2, the stem being secured or retained in position relative to the felloe by a nut 3. The stem is threaded for its full length as at 4, and said threads are interrupted at diametrically opposite sides of the stem by the flat longitudinally extending portions 5, said stem also being provided with a small upper end 6, which is adapted to receive the usual valve cap, not illustrated. The stem, as illustrated, is of the form now universally in use, and in some cases, the nut 3 is employed and other cases, it is dispensed with, this being optional with the user.

My improved dust guard, comprises a tubular body 7, closed at its upper end as at 8, and open at its opposite or lower end; the body being of a diameter approximately the same as that of the stem. The lower edge of the body at diametrically opposite sides, is turned in as at 8', providing a thread engaging portion which is adapted when the body is slipped downwardly over the stem or withdrawn from the same, to lie parallel with the flat faces 5 and when it is desired to secure the body onto the stem, said thread engaging portions are adapted to engage the threads of the stem as in Figs. 2 and 4 by one-quarter rotation of the body. The body when positioned on the stem and pressed downwardly during

the one-quarter rotation of the same is adapted to force a sealing member 10, carried in the upper end of the body tightly into contact with the open upper end of the 5 stem, thus sealing the same and preventing the escape of the air pressure therefrom. This construction enables the guard to be easily positioned on, or removed from the stem, and enables the sealing member to be 10 drawn tightly into contact with the upper end of the stem by a one-quarter turn of the body relative to the stem. The body is of a length approximately one-half of that of the valve stem, thus adapting the same for 15 use in connection with the stems which only project through the felloe a short distance, as it is necessary to enable the sealing member to be drawn tightly into contact with the upper open end of the valve stem that 20 the lower end of the body or guard member fall short of contacting with the nut 3.

In order to enclose that portion of the stem below the lower end of the dust guard, an open shell or sleeve 11 is slidably mounted 25 upon the body 7, in frictional contact therewith, and from the drawings, it will be apparent that when the body is in position, with the sealing member in contact with the open upper end of the stem, that said shell 30 is moved longitudinally thereof, so that the lower end will contact with the nut 3 and enclose the stem. It is desired that this shell be maintained in its adjusted position due to frictional contact with the body 7, 35 however, the centrifugal force of the rotating wheel will also tend to maintain the shell or sleeve in the desired position. To facilitate the removing of the body 7 from the stem and to prevent the shell or sleeve 40 from passing upwardly over the upper end of the body, an enlarged annular portion 12 is formed thereon and if desirable the same may be knurled.

Having thus described my invention what 45 I claim as new and desire to protect by Letters Patent is:—

1. In combination with a threaded valve stem substantially oval in cross section, a sheet metal dust guard for detachably positioning thereon to enclose the same and comprising a pair of telescopic tubular members, one of said members being formed with unbroken side walls and being closed at its outer end, the extreme inner end thereof being 50 inwardly turned or bent at opposite sides to provide thread engaging portions arranged diametrically opposite each other to engage the threads of said stem, and a sealing member within the outer closed end 55 of said first mentioned member, the other of

said members adapted for sliding longitudinally of said first mentioned member and projecting below the inner end thereof and enclosing the base of said valve stem.

2. In combination with a threaded valve 65 stem substantially oval in cross section, a sheet metal dust guard for detachably positioning thereon to enclose the same and comprising a member formed with unbroken side walls and closed at its outer end, the extreme inner edge thereof being inwardly turned or bent at opposite sides to provide thread engaging portions arranged opposite each other to engage the threads of the stem, and a sealing member within the outer closed 70 end of said member, co-operating with said thread engaging portions to hold the cap on the stem.

3. A dust cap for tire valves or the like, comprising a pair of frictionally engaged 80 telescoping members, the inner member of which has means for engaging a valve stem to hold the cap thereon and for sealing the end of said valve stem, said means comprising a sealing gasket positioned within the 85 closed end of the member.

4. A dust cap for tire valves or the like, comprising a pair of frictionally engaged telescoping members, the inner member of which has means for engaging a valve stem 90 to hold the cap thereon and for sealing the end of said valve stem, said means being located a fixed distance apart.

5. A dust cap for tire valves or the like, comprising a shell portion and a valve cap 95 portion telescopically associated therewith, the valve cap portion being provided with a valve stem sealing gasket in its closed end and at its open end with means for directly engaging a valve stem to hold the cap thereon, the shell portion being free from engagement with the valve stem.

6. A dust cap or the like, adapted for enclosing valve stems of various lengths, comprising a pair of frictionally engaged telescoping members, the inner member of which has means for engaging the threads on a valve stem a fixed distance below the top thereof to hold the cap thereon, and a sealing gasket in its closed end adapted to engage the end of the valve stem, and the outer member being free of engagement with the valve stem and adapted to seat against a rim nut or wheel felly.

In testimony whereof I have signed my 115 name to this specification in the presence of a subscribing witness.

CLEVE T. SHAFFER.
